UNITED STATES PATENT OFFICE

OTTO A. MILLER, OF BUFFALO, NEW YORK

CUTTER AND SHAPER HEAD

Application filed December 20, 1928. Serial No. 327,292.

This invention relates to woodworking and more particularly to an improved cutter and shaper cutter head such as is used in rabbeting, chamfering, grooving and otherwise shaping moldings and various articles of wood.

Woodworking implements and shapers heretofore proposed, have been not only elaborate and expensive in their make-up, but also have proven difficult of adjustment and control. A different shaper head has been necessary for each spindle (left and right); a different set of cutters required therefor; and a firm anchorage for the cutter against creeping or loosening during operation on a piece of wood has heretofore been impractically and unsatisfactorily obtained.

The present invention has for its objects to provide an improved cutter head of simple design capable of being used on either left or right spindles; to provide a cutter head having a novel arrangement of seats for the accommodation of the several cutters in either right or left spindle operation; to provide a simple and novel adjustable clamp for each cutter; to provide a novel cutter for use in cooperation with the cutter head; and to improve the cutting edge of the cutter.

The invention further resides in the novel arrangement and combination of parts hereinafter more fully set forth reference being had to the accompanying drawing wherein,

Fig. 1 is a side elevation of my improved cutter head equipped with its cutters and mounted in a position for operating on wood stock.

Fig. 2 is a bottom plan view of the wood-working tool depicted in Fig. 1.

Fig. 3 is a bottom plan view of the cutter head per se.

Fig. 4 is a cross sectional view illustrating a slightly modified form of cutter bit. Figure 5 is a cross sectional view of the cutter bit shown in Figures 1 and 2.

Referring more in detail to the accompanying drawing, the numeral 1 designates my improved shaper cutter head which is clamped on a spindle 2 between the spacing collars 3 by a nut 4.

One face of the cutter head, preferably

the bottom face, is provided with a plurality of chordal seats 5 which are accessible at the opposite ends to the periphery of the head. These seats, illustrated as grooves, have companion slots 6 paralleling the respective 55 grooves for at least a portion of their length and disposed outwardly thereof. The simplest and preferred arrangement restricts the number of grooves to three and disposes them in the form of an equi-lateral triangle about 60 the central or spindle-receiving opening 7 in the head. The ends of the grooves are shown as having their center lines intersecting one another at the periphery so that the width of the cut through the periphery will approximate that of a single groove, thereby affording a maximum length of bearing surface for the individual cutters without unduly removing excessive portions of the peripheral surface of the head.

The cutters are designated by the numeral 8, the same comprising a head-engaging and cutter-supporting rib 9, designed to have sliding fit in its respective groove 5, and an overhanging anchoring body portion 10 which seats flatly upon the body of the cutter head outwardly of the respective groove 5 and at opposite sides of the respective slot 6. Toward the cutting edge 11 the body portion 10 of the cutter is attenuated to a certain extent but still affording a bearing surface or ledge 12 to reinforce and support that portion of the cutter immediately adjacent the cutting edge 11.

The cutter is firmly secured in its adjusted position in the groove 5 by a simple form of clamping means herein depicted as a single bolt or screw 13 which has its head 14 seating on the upper face of the cutter head 1 with its shank passing through the slot 6 and threadedly engaged in a screw-receiving opening in the overlying body portion 10 of the cutter. By simply loosening the clamping bolt the cutter is released so as to permit of the same being projected more or less beyond the periphery of the cutter head by sliding the bolt-carrying cutter along its groove, and after the desired adjustment has been obtained the clamping bolt is tightened 100

so as to firmly secure said cutter at its new adjustment.

The cutter 8, by having a guiding and supporting rib 9 both on its upper and lower sides, is thereby rendered reversible, adapting the single cutter for either right or left spindles. In other words, if the cutter head is to be changed from a right spindle to a left spindle or if the cutter is to be transferred from a cutter head mounted on a right spindle to a cutter head mounted on a left spindle, the clamping bolt 13 is withdrawn from engagement with the cutter, the cutter turned over or reversed so as to project from the opposite end of its seat or groove 5, as indicated at 8' in Fig. 2, the clamping bolt re-engaged with the cutter and set to firmly secure the same in its reversed position. Of course, in the position indicated by the dotted showing 8', the remaining cutters will also be disposed in their reversed order. It will be noted that the ends 5' of the outer wall of each groove 5 lie in the plane of the inner walls of the adjacent grooves so as to contact with and support the cutter of the first groove against chattering.

In lieu of providing a cutter with a rib on its upper and lower sides, there may be provided two sets of cutters one for a right spindle and the other for a left spindle. Such form of cutter is depicted in Fig. 4 wherein the cutter 8^a has a single rib 9^a only.

The cutting face or side of each blade is preferably scaled, as by a milling operation, so as to provide a plurality of very fine corrugations, indicated at 15, which extend into the cutting edge 11 so that when the cutter is ground or sharpened the cutting edge will possess a multiplicity of very fine teeth.

In operation the cutters are first adjusted for the desired depth of cut. The wood stock, indicated at 16, is then positioned on the table, indicated at 17, and brought into operative contact with the cutters. In the particular illustration, the three cutters are operating to provide a rabbet 18 in said stock. If desired cutters having active edges of various forms and shapes may be combined or associated on the single cutter head in order to produce a composite cut on the stock, or one cutter may be used at a time by projecting the same slightly beyond the active arc or path of the remaining cutters. This can be effected without perceptibly throwing the cutter head out of balance. For safety, the cutters are carried on the lower side of the cutter head and the adjustments effected from above, as by applying a wrench to the head 14 of the clamping bolt. By this arrangement the operator is not required to reach over or about the cutters in adjusting them, and is also protected to a large degree from coming into contact with the cutters when the head is rotating.

What is claimed is:

1. In combination a shaper head adapted for mounting on a spindle and having one face provided with a plurality of grooves opening at each end through the periphery of the head, a plurality of cutters, one for each groove having ribs on its opposite sides for selective engagement with its respective groove whereby the cutter may be reversed in its groove and with respect to the shaper head, the disengaged rib being unsupported and free, the forward end of the cutter being provided with a cutting edge extending through both ribs and adjustable for projection through either end of its groove and beyond the periphery of the shaper head, and means engaging the body portion of each cutter intermediate its two ribs for clamping the cutter to the shaper head.

2. A shaper cutter head having a plurality of chordal grooves opening through the periphery thereof with the axes of the grooves intersecting adjacent ones in the periphery, the edges of the kerfs through the periphery being in the planes of the inner walls of the intersecting grooves.

3. A shaper cutter head having chordal-like seats arranged about its axis, and slots paralleling said seats, a cutter engaged with each seat and having a part overlying the respective slot and bearing upon the shaper head at opposite sides of the slot, and a clamping bolt in each slot with its head bearing on the opposite face of the shaper head and its shank threaded into the overlying part of the respective cutter for securing the cutter in an adjusted position.

4. A cutter for shaper heads having a rib extending in the plane of the cutting face and an intermediate bearing ledge extending laterally from between the ribs and broadening into an anchoring body portion adjacent the inner end of the cutter, said body portion formed with an anchor-receiving opening.

5. A cutter for shaper heads having a body with a cutting face and a pair of ribs extending from opposite sides of the body for substantially the full length thereof and in the plane of the cutting face, said body being enlarged adjacent the inner end of the cutter in a plane perpendicular to the cutting face to form a cutter anchoring portion, said portion being formed with a screw threaded opening to receive an anchoring bolt.

6. A shaper cutter head having a plurality of chordal grooves opening through the periphery thereof with the axes of the grooves intersecting adjacent ones in the periphery, the ends of the outer walls terminating in the planes of the inner walls of the adjacent grooves to serve as supports for cutters when arranged in said latter grooves, and cutters arranged in the grooves and obtaining support at opposite sides in the periphery from

the side walls of the respective kerfs formed in the periphery by said grooves.

7. A shaper cutter head having chordal-like seats arranged in one face and about its axis and opening through the periphery thereof, and slots disposed outwardly from and paralleling said seats, said slots terminating short of the ends of the seats, a cutter for each seat having a rib engaging therein and having an enlarged portion overlying the adjacent slot, said enlarged portion being provided with an opening, and a bolt for each slot arranged therein with the head of the bolt engaging the opposite face of the cutter head, said bolt passing through the slot and into the opening of said enlarged portion of the adjacent cutter for securing the cutter to the seat-containing face of the cutter head, said enlarged portion giving reinforcement to the cutter, said chordal-arranged cutters being unsupported on their sides opposite to their seat-engaged sides.
